[57] CLAIM

The ornamental design for a trash funnel, as shown and described.

DESCRIPTION

FIG. 1 is a perspective view of the trash funnel showing my new design;

FIG. 2 is a side elevational view thereof, the opposite side elevational view being a mirror image of that shown;

FIG. 3 is a top plan view thereof;

FIG. 4 is a front elevational view thereof;

FIG. 5 is a bottom plan view thereof; and

FIG. 6 is a rear elevational view thereof.
